US00D855970S

(12) **United States Design Patent** (10) **Patent No.:** **US D855,970 S**
(45) **Date of Patent:** **** Aug. 13, 2019**

(54) **CATHETER PACKAGE ASSEMBLY**

(71) Applicant: **Hollister Incorporated**, Libertyville, IL (US)

(72) Inventors: **David Hannon**, Ballina (IE); **Martin McMenamin**, Lifford (IE); **Adam J. Foley**, Swords (IE); **Paul C. Fletter**, Mt. Prospect, IL (US); **Marine V. G. Richard**, Carrières sur Seine (FR)

(73) Assignee: **Hollister Incorporated**, Libertyville, IL (US)

(**) Term: **15 Years**

(21) Appl. No.: **29/599,662**

(22) Filed: **Apr. 5, 2017**

Related U.S. Application Data

(62) Division of application No. 29/528,628, filed on May 29, 2015, now Pat. No. Des. 789,075.

(57) **CLAIM**

The ornamental design for a catheter package assembly, as shown and described.

DESCRIPTION

FIG. 1 is a perspective view of a catheter package assembly showing our new design.

FIG. 2 is a right side elevational view of the catheter package assembly of FIG. 1.

FIG. 3 is a left side elevational view of the catheter package assembly of FIG. 1.

FIG. 4 is a rear elevational view of the catheter package assembly of FIG. 1.

FIG. 5 is a front elevational view of the catheter package assembly of FIG. 1.

FIG. 6 is a top plan view of the catheter package assembly of FIG. 1; and,

FIG. 7 is a bottom plan view of the catheter package assembly of FIG. 1.

The broken lines depict portions of the article that form no part of the claimed design.

1 Claim, 3 Drawing Sheets
